United States Patent Office.

W. P. PUGH, OF HIGH POINT, NORTH CAROLINA.

Letters Patent No. 95,377, dated September 28, 1869.

IMPROVED MEDICATED SOAP.

The Schedule referred to in these Letters Patent and making part of the same.

I, W. P. PUGH, of High Point, in the county of Guilford, in the State of North Carolina, have invented a new and highly efficacious Medicated Soap.

The nature of my invention consists in incorporating into any innocuous alkaline detergent compound a proper proportion of farina of any of the ordinary cereals and *Hydrargyri cyanureum*.

I take common hard soap, one pound; sal-soda, four ounces; farina, eight ounces; *Hydrargyri cyanureum*, one scruple; aqua ammonia, one ounce; common water, one pint.

Place the water in a vessel over the fire, and when it reaches the boiling-point, add in succession the soap, cut into thin slices, the sal-soda, the farina, the *Hydrargyri cyanureum*, previously dissolved in one ounce of common water, and, lastly, the aqua ammonia; remove from the fire, and decant while hot into shallow vessels, to divide into cakes of suitable size while cooling.

The advantages and benefits of this combination result from the action of the alkali upon the farina, converting it into a vegetable glycerine, the action of which, combined with the detergent qualities of the soap and the alterative influence of the cyanuret, constitutes one of the most prompt and reliable remedies for all manner and every variety and grade of cutaneous disease, from simple scabies to the most difficult curable forms of phagedenic ulceration.

I claim, as my invention, the foregoing combination as a whole, and their application, in said combination, to the cure of disease in man or beast, and to the destruction of parasitic insects or vegetables on man or beast.

W. P. PUGH, M. D.
